UNITED STATES PATENT OFFICE

LOUIS E. PARENT, OF CLAREMONT, NEW HAMPSHIRE, ASSIGNOR TO CLAREMONT WASTE MANUFACTURING COMPANY, A CORPORATION OF NEW HAMPSHIRE

ROTARY CUTTER

Application filed September 7, 1927. Serial No. 218,008.

My invention relates to rotary cutters.

It has for its object to provide improved cooling means for the tool carrying bed of such a cutter, and more particularly a flock cutter, whereby the operating temperature of the device is kept down, this being of especial importance in a flock cutter because of the danger from fire. A still further object of my invention is to provide improved cooling means of the tank type wherein the temperature of the water adjacent the bed is substantially reduced, air pockets are minimized, a greater area of the bed is cooled, and the tool adjusting means is protected from the water. These and other objects and advantages of my improved construction will, however, hereinafter more fully appear.

In the accompanying drawings I have shown, for purposes of illustration, one embodiment which my invention may assume in practice.

In these drawings,—

Figure 1 is a central longitudinal sectional view of a flock cutter equipped with my improvement;

Fig. 2 is a transverse sectional view of the same;

Fig. 3 is a sectional view on line 3—3 of Fig. 4;

Fig. 4 is a sectional view on line 4—4 of Fig. 3, and

Fig. 5 is a sectional view on line 5—5 of Fig. 3.

In this illustrative construction, I have shown a flock cutter of well known type including a tool carrying cylinder 1 cooperating with knives 2 carried in a bed 3 and disposed beneath the same and adjustable from the bottom by means of members 4 disposed as usual in series extending transversely across the bed and accessible through transverse slots 5 in the bottom of the bed.

In my improved construction it will be noted that the bed 3 is suspended in a water tank 6 in the form of a series of communicating water chambers separated by transverse baffles 7 and disposed beneath the bed 3 and extended up on opposite sides of the latter so as to cool not only the whole of the bottom and sides of the bed, but areas in contact

with the flock at and above each side of the same. Herein, this tank 6 is relatively deep, though its depth may obviously be varied, and provided with a removable bottom plate 8, suitably attached thereto to cooperate with the baffles 7 to form a series of water chambers. The plate 8 is also suitably connected to the members forming the walls of the tank 6 by attaching means, herein in the form of screws 9, it being understood that suitable lagging or the like (not shown) is provided to prevent leakage. Herein it will also be noted that an inlet pipe 10 delivers upward through one end of the bottom plate 8, herein in the left hand end (Fig. 1) and into the left hand chamber, and that the immediately adjacent baffle 7 on the right is provided with an aperture 11 at one end and near its top through which the water may flow to the next chamber. The baffle 7 on the opposite side of this second chamber is in turn provided with an aperture 12 at the top of the opposite end thereof, while the next right hand baffle is provided with an aperture 13, and the next with an aperture 14, all arranged in staggered relation. Thus it will be noted that, since these apertures are disposed one on one side of the knife bed and the next on the other, the cooling water entering through the pipe 10 is caused to flow into the first chamber transversely and out through the aperture 11, and in a reverse direction transversely of the next chamber to the aperture 12, and so on reversely through the apertures 13 and 14 until it comes to the right hand end chamber, the water thus always passing out of each chamber at the top. Here it will also be noted that at the top of the chamber at the right a pair of upwardly opening outlets 15, 16 is provided, one of these being disposed on each side of the bed. Attention is also directed to the fact that each of the slots 5 in the bottom of the bed 3 is also covered on its under side by suitable lagging 17 adapted to protect the members 4 from the cooling water and removable when desired to permit access to be had to the members 4.

Thus it will be observed that the cool water entering at the bottom of the left hand end of the bed flows through a baffled path trans-

versely back and forth through the bed, and that the heated water is discharged through each baffle at the top, thereby tending to keep the bed at minimum temperature. More 5 specifically, the water is caused to circulate in such manner as to prevent the concentration of immobile heated water at the top, i. e. adjacent the bottom of the bed, and the consequent overheating of the bed heretofore resulting where a tank has been placed under 10 the bed, with pipes at the opposite ends of the bottom of the tank so that the cool water simply by-passes beneath the heated water; my improved baffling and circulating means 15 requiring circulation of the water adjacent the bed and constant replacement of any heated water by cool water in such manner as to result in a substantially lower temperature of the water adjacent the bed and of the bed 20 and knives. It will be observed that in my improved construction any tendency of the device to become airbound, with the released air at the top and under the bed, is minimized. Attention is also directed to the fact 25 that the cooling water acts upon the whole knife bed, bottom and sides, and to the further fact that, at the same time that the water underlies the adjusting means for the bed knives, it is also made possible to protect 30 these in such manner as to keep them readily adjustable when desired. It will of course also be understood that whenever it is desired to adjust the knives in the bed it is only necessary to remove the bottom plate 35 and lagging strips, and that when the bottom plate 8 is removed it is entirely unnecessary to disconnect the discharge piping. These and other advantages of my improved construction will, however, be clearly apparent 40 to those skilled in the art.

While I have in this application specifically described one embodiment which my invention may assume in practice, it will be understood that the invention is not limited 45 thereto but may be modified and embodied in various other forms without departing from its spirit or the scope of the appended claims.

What I claim as new and desire to secure 50 by Letters Patent is:

1. In combination, a tool carrying bed, an underlying water tank therefor, supply and discharge connections for said tank, and means in the tank and having portions providing a passageway in the top of the tank 55 extending between said supply and discharge connections, for circulating the water in the top of said tank and insuring a circulation relative to the rest of the water in the tank of said water in the top of the latter which is in contact with the bed.

2. In combination, a tool carrying bed, an underlying water tank, and baffle means in the tank and supply and discharge connections for the latter co-operating with said 60

baffle means insuring circulation of the water in the tank which is adjacent said bed.

3. In combination, a water tank, a tool carrying bed suspended therein and having its bottom and sides cooled thereby, and co-operating means in said tank and supplying water thereto and discharging the same therefrom; maintaining a circulation of the water which is in contact with said bed. 70

4. A tool carrying bed having an underlying water chamber and baffle means in the latter providing apertures therein disposed in staggered relation to produce a tortuous flow in contact with said bed. 75

5. A tool carrying bed having an underlying water chamber and baffle means in the latter providing apertures therein disposed in staggered relation to produce a tortuous flow in contact with said bed, said baffles being transversely disposed. 80

6. A tool carrying bed having an underlying water chamber and transverse baffle means in the latter having apertures therein disposed in staggered relation, said apertures being disposed at the top of said baffle means. 85

7. A tool carrying bed having a plurality of water chambers beneath the same separated by transverse baffles having apertures at their upper ends, said apertures being disposed in staggered relation and one end chamber having an inlet and the other end chamber an outlet. 90

8. A tool carrying bed having a plurality of water chambers beneath the same separated by transverse baffles having apertures at their upper ends, said apertures being disposed in staggered relation and one end chamber having an inlet and the other end chamber an outlet, said inlet being a bottom inlet and the outlet a top outlet. 100

9. In combination, a tool carrying bed, a series of cooling tanks underlying the same and extending upward beyond the sides thereof, said tanks having communication with one another through apertures disposed in staggered relation in said upwardly extending portions. 110

10. In combination, a tool carrying bed, a series of cooling tanks underlying the same and extending upward beyond the sides thereof, said tanks having communication with one another through apertures disposed in staggered relation in said upwardly extending portions, a bottom inlet connected to one end tank, and a top outlet connected to the other. 115

11. In combination, a tool carrying bed, a series of cooling tanks underlying the same and extending upward beyond the sides thereof, said tanks having communication with one another through apertures disposed in staggered relation in said upwardly extending portions, a bottom inlet connected to one end tank, and a top outlet connected to the other, said top outlet comprising out- 120 125 130

let passages connected to each of said upwardly extending portions of said end tank.

12. In combination, a knife bed adapted to have its bottom and sides suspended in cooling water, a tank receiving the same and immersing said bottom and sides, and means for maintaining a circulation of the water in contact with the bottom and sides of said bed.

13. In combination, a knife bed having its bottom and sides suspended in cooling water, a tank receiving the same, and means for maintaining a circulation of the water in contact with said bed including transverse baffles having staggered apertures above the bottom of said bed.

14. In combination, a knife bed having its bottom and sides submerged in cooling water, a tank receiving the same, and means for maintaining a circulation of the water in contact with said bed including transverse baffles having staggered apertures above the bottom of said bed, a bottom inlet at one end of the tank, and top outlet means at the opposite end thereof above the sides of the bed.

15. A water cooled tool bed having a water chamber beneath the same and provided with transverse baffles having apertures alternately at opposite sides of the same and an inlet at one end thereof and outlet means at the opposite end thereof.

16. A water cooled tool bed having a water chamber beneath the same and provided with transverse baffles having apertures alternately at opposite sides of the same and an inlet at one end thereof, and outlet means at the opposite end thereof said inlet being at the bottom and said outlet means at the top.

17. In a water cooled tool bed, means forming a tool chamber, transverse ribs below the same and at opposite sides thereof, said ribs having staggered apertures along the length of the bed and at the sides thereof, a bottom under said ribs forming a water chamber, and inlet and discharge means at opposite ends of said tool chamber.

18. In combination, a tool carrying bed having adjusting means accessible from its bottom, sealing means for said adjusting means removable from the bottom of said bed, and a cooling water tank in which said bed and sealing means are submerged and having provision for permitting access to said sealing means.

19. A tool carrying bed provided with slots in its bottom, knives carried thereby having adjusting means extending into said slots, means sealing said slots and removable from the bottom of said bed, and cooling means supplying cooling water to the under side of said bed and of said sealing means likewise permitting access to said removable sealing means.

20. In combination, a water tank, and a tool carrying concave immersed therein with its bottom and its sides within the liquid.

21. In combination, a water tank, and a tool carrying concave immersed therein with its bottom and its sides within the liquid and laterally extending portions above its sides likewise cooled by the liquid.

22. In combination, a water tank, a tool carrying concave immersed therein with both its bottom and its sides within the liquid, and means for prescribing a circulation of liquid in contact with the sides and bottom thereof.

23. In combination, a water tank, a tool carrying concave projecting into the same, and circulating means inhibiting flow along the bottom of the tank and prescribing a path of liquid flow in contact with said concave.

24. In combination, a water tank, a tool carrying concave extending into the same, and water circulating means including baffle means in said tank so disposed as to divide the tank into communicating compartments.

25. In combination, a water tank, a tool carrying concave extending into the same, and water circulating means including baffle means in said tank so disposed as to divide the tank into communicating compartments having communication only adjacent said concave.

26. In combination, a water tank, a tool carrying concave extending into the same and having its tools adjustable from its bottom, and water circulating means including baffle means in said tank so disposed as to divide the tank into communicating compartments through certain of which said tools are adjustable.

27. The combination with a water tank, of a tool carrying concave having its bottom in the latter and apertures in its bottom, tool adjusting means in said apertures, and sealing means covering said apertures and between said adjusting means and the liquid in said tank and removable from the bottom of the concave.

28. In combination, a tool carrying bed, an underlying water tank therefor, tank flow connections spaced longitudinally of the bed and including a top outlet, and co-operating means in the tank for insuring a circulation in contact with the bed and transversely of the latter of the water film in the tank in contact with the bed.

In testimony whereof I affix my signature.

LOUIS E. PARENT.
